UNITED STATES PATENT OFFICE.

CHARLES ROSIER, OF NEW YORK, N. Y.

PRESS FOR TROUSERS.

1,310,297.

Specification of Letters Patent. Patented July 15, 1919.

Application filed June 29, 1918. Serial No. 242,578.

To all whom it may concern:

Be it known that I, CHARLES ROSIER, a citizen of the Republic of France, residing at 2095 Tiebout avenue, Bronx, New York city, 5 New York, have invented certain new and useful Improvements in Presses for Trouser, of which the following is a specification.

This invention relates to presses for garments and particularly for trousers, and an 10 object of the invention is to restore and preserve the proper shape and provide the desirable creases of the legs of trousers by simple and effective means which may be readily operated by any individual without requiring the use of steam or dry heat or the 15 practice of methods usually pursued in pressing and shaping trousers. A further object of the invention is to minimize the cost of trouser-pressing devices and mechanism 20 and likewise the expense of pressing and properly shaping trousers.

With these and other objects and advantages in view, the invention consists in the construction and arrangement of the several 25 parts which will be more fully hereinafter described and claimed.

In the drawings:

Figure 1 represents a perspective view of 30 a garment pressing device specially designed for use with trousers and embodying the features of the invention, the pedestal of the device being broken away.

Fig. 2 is a top plan view of the improved device.

Fig. 3 is an end elevation of the improved 35 device showing the pedestal thereof broken away and the pressing members held down in operative position relatively to a pair of trousers.

Fig. 4 is a view similar to Fig. 3 showing 40 the pressing members elevated or released from the trousers.

The device as shown by the drawings and as will be hereinafter specified in detail is 45 particularly designed and arranged for pressing trousers, but it will be understood that the same might be employed for pressing other garments, and the improved device is intended to have a general application and 50 is not limited to the precise features of construction which will be hereinafter enumerated but may be varied to adapt the invention to various applications within the scope of the appended claims.

The numeral 5 designates a supporting 55 pedestal which may be held by any suit-

able form of base that may be portable or stationary, but it is preferred that the press as a whole be portable. Centrally secured on the upper end of the pedestal is a board, 60 plate or table 6 of suitable dimensions and material. Movably mounted over the board, plate or table 6 are two pressing members 7 preferably of the same length as the board, plate or table 6 but each of materially less 65 width than the latter, the members 7 in the present instance being disposed to operate on opposite sides of the longitudinal center of the board, plate or table 6. The pressing members 7 may also be of suitable material 70 and are connected for simultaneous movement by cross-straps or bars 9, one adjacent to the opposite extremities of the pressing members. The straps or bars 9 are applied to the upper surfaces of the members 75 and extend across the space between the inner opposing edges of said members and on the opposite ends of each strap or bar 9 is a fulcrum bracket 10 comprising upwardly 80 projecting sides or arms 11 with inwardly extending heads 12 substantially elliptical in contour and having elongated straight slots 13 which extend transversely with relation to the pressing members 7 and the board, plate or table 6. A clamping lever 14 is operatively 85 mounted between each pair of sides or arms 11 of each bracket and projecting outwardly from opposite sides of this lever are fulcrum pins or studs 15 which loosely or 90 slidably engage the slots 13 of the heads 12, the pins or studs 15 being located nearer the outer than the inner end of the lever to thereby dispose the longer portion of the lever inwardly over and above each strap or bar 9. The inner extremity of each lever is formed 95 as a handle or grip 16 and the outer end is provided with a hook-like terminal 17 over which is fitted the upper terminal loop 18 of a spring 19 extending downwardly into a socket 20 in the board, plate or table 6 at 100 a distance outwardly beyond the outer edge of the adjacent member 7. There are four of the clamping levers 14 and as many springs 19, the springs, as nearly as practical, having a uniform tension on the outer ends 105 of the levers 14. The intermediate portion of each lever 14 is provided with a cam 21, the pins or studs 15 forming the eccentric fulcrum means for the cam, and below the said pins or studs 15 the cams 21 have an 110 other pair of pins or studs 22, the pairs of pins or studs 15 and 22 being in such spaced

relation that the lower pair of pins or studs will bear against the lower edges of the heads 12 and also against the lower portions of the inner curved end edges 23 of said heads. 5 The lower edge 24 of the cam is arcuate and is adapted to move between the sides or arms 11 and institute a downwardly-directed pressure relatively to the brackets, the straps or bars 9, and the members 7 when the levers 10 are moved downwardly at their inner ends against the resistance of the springs 19. When the lever 14 is closed, as shown particularly by Figs. 1 and 3, the lower pair of pins or studs 22 are forced into curved 15 seats 25 at the intersection of the inner and lower edges of the sides or arms 11 and the heads 12, and when the said lower pair of pins or studs are in the seats 25, the lever cannot be further forced downwardly and 20 at the same time a locking action ensues in view of the fact that the upper pins 15 shift longitudinally in the slots 13 of the heads 12 to the outer ends of said slots, as clearly illustrated by Fig. 3. The cams do not 25 engage the base members of the brackets 10 and the pressure exerted on the members 7 is of a yielding nature, due to the fact that the resistance to the closure of the levers 14 is set up solely by the springs 19. Moreover, 30 the levers 14 will not become accidentally loose or displaced from full locking positions or depressions owing to the shifting movement of the pins 15 in the slots 13 of the heads 12. When the levers 14 are released, they are forced upwardly at their inner ends and the pins 15 slide inwardly in the slots 13 until they reach the inner ends of said slots, as shown by Fig. 3, and at the 35 same time the springs, tending to resume their normal condition, operate to draw the outer ends of the levers downwardly and 40 raise the pressing members 7.

In pressing a pair of trousers, the legs are brought together with side seams against 45 side seams and the ends coincident and then drawn smoothly over the board, plate or table 6 under the pressing members 7, and after the trousers have been properly adjusted or placed on the board, plate or table 50 6, the members 7 are closed or forced against the trouser legs by closing the levers 14, as shown by Figs. 1 and 3. The trousers may be allowed to remain in the press as long as desired or until the legs have been properly 55 shaped and all irregular form thereof removed. It will be understood that, in the operation of applying the trousers on the board, plate or table 6, the free ends of the trousers may be first secured by closing one 60 set of levers 14 before the remaining set of levers are closed, and that prior to closing the last set of levers the trouser legs may be stretched or drawn taut with sufficient tension to give them the proper shape, especially to remove distortion or bagging pro- 65

jections at the knees, and then the last set of levers may be secured to hold the trousers in proper shape as desired and all of the levers remain in locked or closed positions with the pressing members 7 firmly against the trouser legs as long as may be necessary to restore the trousers to proper shape. 70

Among other important advantages of the improved garment press which is especially adapted for trousers is that it may be operated by any one and without requiring a particular knowledge of mechanical construction, and, furthermore, the shaping operation may be effected without resorting to either dry or moist heat. Moreover, in view of the simplified structure of the improved press, a large number of the same may be installed in each pressing shop or tailoring establishment to operate simultaneously on a number of pairs of trousers at 80 one time, or, if desired, the improved device may be purchased and used by an individual domestically. As heretofore indicated, it is possible to press other garments by the improved device with the same effectiveness as 85 in operating therewith upon trousers. 90

I claim as my invention:

1. In a device of the class specified, a table, pressing members disposed on opposite sides of the table and connected for simultaneous operation and provided with means for always holding them in parallel relation to the table and rendering them uniformly movable throughout their entire lengths equally toward and from the table, a lever clamping device at each extremity of each pressing member, and resilient devices vertically disposed between the outer ends of the clamping devices and table. 95

2. In a device of the class specified, a table, pressing members disposed on opposite sides of the longitudinal center of the table and connected for simultaneous operation, a clamping lever at each extremity of each pressing member and having shiftable fulcrum means, and resilient devices connected to the outer ends of the lever and table. 100

3. In a device of the class specified, a flat table, spaced pressing members extending over the table on opposite sides of the longitudinal center of the table and connected at opposite extremities for simultaneous and uniform operation, a clamping lever at each extremity of each pressing member and having shiftable fulcrum means and stop means to limit the closing movement of the lever, and a resilient connecting device between the outer end of each lever and the table. 115

4. In a device of the class specified, a flat table, a pair of spaced pressing members rigid throughout their entire lengths and arranged over the table on opposite sides of the longitudinal center of the table and provided with means for always holding them 120

in spaced relation above the table throughout their entire lengths to give a clearance between opposite extremities of the members and table, and clamping means at each extremity of and movable inwardly and outwardly over the pressing members and resiliently connected to the table.

5. In a device of the class specified, a flat table, a pair of longitudinally extending spaced pressing members rigid throughout their entire lengths and provided with means for maintaining them in parallel relation to

the table and for connecting them for simultaneous operation, and levers movable transversely inwardly and outwardly over the members and each having a spring connected to its outer end and to the table.

In testimony whereof I have hereunto set my hand in presence of two subscribing witnesses.

CHARLES ROSIER.
